HIGH FREQUENCY OSCILLATION SYSTEM
AND METHOD

George C. Southworth, Ridgewood, N. J., assignor to American Telephone and Telegraph Company, a corporation of New York

Application October 9, 1934, Serial No. 747,605

29 Claims. (Cl. 178—44)

A principal object of my invention is to provide for the generation of high frequency alternating currents for the propagation of electric waves from one place to another. The alternating currents referred to may be conduction currents, or displacement currents in a dielectric, or both. Another object is to provide improved electron discharge apparatus for use wherever such apparatus may be of advantage. A more special object of my invention is to provide for the generation of displacement currents to be propagated as electromagnetic waves in dielectric guides. Another object is to provide oscillation generators in operative combination with respective dielectric guides. A further object in this connection is to provide a suitable design and dimensions of the associated guide and generator so that a desired frequency will be generated. Another object is to provide a high frequency oscillation generator in combination with a dielectric guide so that waves of a desired type will be propagated. Another object is to accomplish some or all of the foregoing objects by causing electrons to oscillate in suitable paths, so that the desired waves will be generated in the lines of force which extend therefrom. Another object is to combine an oscillation generator with a dielectric guide and a reflector so that the period of waves in the guide as determined by the reflector will enforce a corresponding period on the generator. In some cases my invention may be realized by the use of vacuum tubes built in combination with such guides; in other cases spark gap oscillators may be built in combination with such guides.

All the foregoing objects and aspects of my invention, and other objects and advantages thereof, will be made apparent in the following specification in which I disclose a limited number of examples of practice according to the invention. The following specification has relation more particularly to these particular examples of the invention, and its scope will be indicated in the appended claims.

Referring to the drawings, Figures 1 and 1a are diagrammatic longitudinal and transverse sections of a metal-sheath air-core dielectric guide showing the electric and magnetic lines of force for symmetric electric waves therein; Figs. 2 and 2a are such sections for symmetric magnetic waves; Figs. 3 and 3a are such sections for asymmetric electric waves; Figs. 4 and 4a are such sections for asymmetric magnetic waves; Fig. 5 is a diagram showing electromagnetic waves as generated by the oscillation of an electron; Fig. 6

is a diagram showing such waves as generated by the oscillation of two opposite charges in opposite phase; Fig. 7 is a diagram showing the waves generated by opposite charges oscillating in opposite phase along paths which are arcs of a circle; Fig. 8 is a longitudinal section of a combined dielectric guide and three-electrode tube for the generation of symmetric electric waves; Figs. 9, 9a and 10 are respectively two cross-sections and a longitudinal section of a combined dielectric guide and three-electrode tube for the generation of asymmetric electric waves; Fig. 11 is a longitudinal section of a combined guide and two-electrode tube for generating and propagating symmetric magnetic waves; Fig. 12 is a detail cross-section of the same; Fig. 13 is a curve diagram exhibiting a certain quantitative relation involved in the operation of this apparatus; Fig. 14 is a longitudinal section of apparatus somewhat like Fig. 11, but with three electrodes instead of two; Fig. 15 is an enlarged cross-section of the same apparatus; Fig. 16 is a corresponding cross-section showing a modification; Fig. 17 is a cross-section of the vacuum tube part of apparatus for generating and propagating asymmetric magnetic waves; Fig. 18 is a cross-section showing a sieve for purifying the waves generated by the apparatus of Fig. 17; Fig. 19 is a longitudinal section of a combined dielectric guide and spark gap for the generation and propagation of symmetric electric waves; Fig. 20 shows a modification for the same purpose; Fig. 21 is a longitudinal section of spark gap apparatus for asymmetric electric waves; Fig. 22 is a cross-section of the same; Figs. 23 and 24 are respectively longitudinal section and cross-section of spark gap apparatus for asymmetric magnetic waves; Fig. 25 is a longitudinal section of apparatus for symmetric magnetic waves; Fig. 26 is a perspective of a detail part thereof; and Fig. 27 is a simplified diagrammatic cross-section.

The nature of the electric waves in a dielectric guide depends somewhat on the shape of the cross-section of the guide. For the sake of definiteness, the examples of the invention here to be described will involve guides of circular cross-section. A dielectric guide may or may not be metal sheathed, but in the examples of the invention to be shown here, metal sheathed guides will be represented. In any case, a dielectric guide from one place to another place is a body of dielectric extending continuously from the one place to the other and bounded laterally by a dielectric discontinuity. There are various types

of dielectrically guided waves which may be propagated in a dielectric guide, as set forth more fully in my copending applications Serial No. 661,154, filed March 16, 1933, and Serial No. 701,711, filed 5 December 9, 1933, but in this specification, we shall consider only four, namely, symmetric electric (E_0), symmetric magnetic (H_0), asymmetric electric (E_1), and asymmetric magnetic (H_1). These various types are designated as electric or 10 magnetic according as they have their principal components of electric or magnetic force in the direction of propagation, and they are symmetric or asymmetric according as the lines of force are or are not symmetrically disposed about the guide 15 axis. In the case of asymmetric waves, the term will here be restricted to waves whose lines of force having components in the direction of propagation are all approximately symmetric to a single plane containing the axis of the guide, but the 20 plane not intersected by any of those lines. These four types of waves are shown in Figs. 1, 1a, 2, 2a, 3, 3a, 4 and 4a, in which the continuous lines represent lines of electric force and the dotted lines represent lines of magnetic force. In all 25 these figures a metal sheathed guide is shown. The sheath or shell would actually be relatively much thinner than indicated. The lines of electric force in the dielectric core correspond to "displacement currents", but when they are continued in the conductive shell, they link through electrons and protons in alternation and correspond to conduction currents. At the very high 30 frequencies considered, both electric and magnetic lines in the shell will lie very close to its 35 inner surface, but the shell is shown thick so the lines therein can be represented clearly.

In many of the devices disclosed hereinafter, certain electrons in a vacuum tube are constrained to oscillate in definite patterns, and we 40 can look upon the waves in the guide as traveling wave shapes in the lines of force which proceed directly from those electrons, or as resultants obtained by combining such shapes in various lines of force.

An electron at rest may be regarded as having 45 lines of force extending straight in all directions therefrom. Consider one such line AD extending horizontally to the right from a stationary electron at A, in Fig. 5. Let this electron oscillate in a simple harmonic motion along the straight line segment ABC which extends at a right angle to the line AD. When the electron 50 has gone from A to B, the part AA₁ of the line AD will be shifted to BA₁. When the electron reaches C the part AA₂ will be shifted to CB₂A₂. Going on, when the electron gets back to B the initial line of force AD will have become 55 BC₃B₃A₃D. It is easy to visualize the ultimate shape of the line of force after many such oscillations; it will lie between two hyperbolas whose asymptotes are BB₄' and BB₂B₃B₄. At any one instant, there will be this wavy line of force lying 60 between hyperbolas diverging to the right; and as time progresses, these waves in the line will progress to the right.

If a group of electrons and an equal positive charge oscillate in opposite phase with simple harmonic motion over the line ABC in Fig. 5, their lines of force will compound to give resultant waves as shown in Fig. 6.

If electrons oscillate with simple harmonic motion along arcs of the circle seen in perspective at ABCB' in Fig. 7, and if equal positive charges oscillate in opposite phase along the same circle, 75 the resultant wave will consist of transverse cir-

cular lines of force progressing to the right. In the waves of Fig. 6 the lines of electric force have components in the direction of propagation; therefore they are electric waves. The lines of magnetic force in Fig. 6 are circles, all centered at the mean point of the said electrons and positive charges, and perpendicular to the plane of the paper and have no components in the direction of propagation. In Fig. 7 the lines of electric force are in circles perpendicular to the direction of propagation, and the lines of magnetic force have components along the direction of propagation; accordingly, the waves of Fig. 7 are magnetic waves.

Referring to Fig. 8, this shows a longitudinal section of a dielectric guide having a metallic cylindrical shell 3 enclosing an air core 7 and extending indefinitely to the right. Near the axis of this shell lies an electron-emitting filament-cathode 5. Surrounding this cathode 5 is the cylindrical plate electrode 1, conductively connected with shell 3 at 8. The space is evacuated within the cylindrical metal wall 1 and the glass end walls or seals 9 at the right and 9' at the left. Surrounding the cathode 5 within the plate electrode 1 is the coaxial cylindrical grid 6.

An inner coaxial cylinder 2 lies at the left with its right end tapered and extending into the corresponding end of the grid 6. The end of this inner tube 2 and the end of the grid 6 lap past each other with a segment of the glass seal 9' between them, but with conductive connections through the glass seal, as indicated by the reference numeral 10. The plate electrode 1 and the grid 6 serve as a concentric conductor system in continuation with the system 3'-2, having the same ratio of outer and inner radii and therefore the same characteristic impedance.

Lying transversely across the annular space between the part 3' of the shell 3 and the inner coaxial shell 2 is a metallic reflector consisting of two parts 4 and 4' with an insulating layer 4" between them. It will readily be seen that the shell 3' and the inner shell 2 are insulated from each other for direct currents though virtually they are conductively connected through 4 and 4' for high frequency alternating currents.

Relatively to the cathode-filament 5, the grid 6 is strongly positive and the surrounding plate 1 is negative. Many electrons from the cathode 5 are accelerated in radial paths to the grid and pass through its openings but are reversed by the strongly negative plate 1. Thus such electrons may oscillate in radial paths through the openings of the grid 6 several times before they are captured by the grid. Such an electron, subject to forces which tend to bring it back to a mean position, may be said to be subject to an equilibrium field. Any such electron oscillating along a radial path has waving lines of force extending right and left therefrom, such as pictured in Fig. 5. Between the axis of the tube 3 and the upper section of that tube shown in Fig. 8 there will be a train of waves extending to the right like those shown in Fig. 6. Similarly, there will be such a train below the axis and extending to the right. Likewise, there will be such wave trains on each side of the axis in any plane containing the axis.

The waves progressing to the left in the annular space between the cylindrical shells 3' and 2 are represented by radial lines of force so that said shells 3' and 2 constitute the two conductors of a concentric conductor system along which transmission takes place from right to left. The waves transmitted in this way are reflected by 75

the reflector 4-4' and proceed thence from left to right along the concentric conductor system, whose two conductors are 3' and 2 merging respectively into the members 1 and 6. The adjustments of electromotive forces and of dimensions, especially the longitudinal adjustment of the reflector 4-4', are made and related so that when the reflected waves arrive at the grid 6, their lines of force are in the same direction as the motion of the respective electrons from which they originated. Thus the oscillatory frequency of the electrons is enforced by the period of the wave travel therefrom to the reflector 4-4' and back. The adjustable reflector 4-4' serves not only to return the reflected wave in proper phase, but to get a relation of the elements involved that is most suitable for efficient operation.

The circuits of the three-electrode vacuum tube 1-9-9' are shown schematically at the left of Fig. 8. The tubular member 2 serves as grid power lead and as a shield for the filament leads against high frequency alternating currents.

The characteristic impedance of the concentric conductor system 3'-2 is given by the formula

$$Z=138.2 \log_{10} R/r \quad (1)$$

in which R and r are the outer and inner radii of the concentric conductor system. A convenient practicable value for this impedance is 20 ohms; it follows from the formula that the corresponding ratio of the two radii should be 1.4. The characteristic impedance of the dielectric guide 3-1 extending to the right should match the characteristic impedance of the concentric conductor system on the left. The formula for the characteristic impedance of a metal-sheathed air-core dielectric guide for symmetric electric waves is given by the formula

$$Z=30\sqrt{1-f_c^2/f^2} \quad (2)$$

in which f is the frequency of the waves and f_c is the critical or limiting frequency of transmission through such a guide. The critical frequency f_c , expressed in megacycles, is related to the guide radius by the formula

$$f_c=11,450/R \quad (3)$$

The radius R of the dielectric guide at the right is the same as the outer radius of the concentric conductor system. A convenient value to be assigned for the frequency f is 3×10^9 cycles per second. This determines the critical frequency according to Formula 2, assuming the same characteristic impedance, 20 ohms. Then, by Formula 3, the minimum radius R for guided wave transmission is determined and is found to be about 5 centimeters.

As shown and described in connection with Fig. 8, the system is adapted for the generation and propagation of electromagnetic waves in a dielectric guide; more particularly, the waves are of symmetric electric type and the guide has a metal shell with an air core. If it is desired to generate and propagate electric waves in a normal concentric conductor system, this can be accomplished by a simple modification of Fig. 8 which consists merely in removing the annular reflector 4-4' and placing a complete disc reflector across the tube 3 at the proper distance on the right of the vacuum tube 1-9-9'. In this case the dielectric waves entering the guide 3 at the right will be reflected back and reenforce the electric current waves with radial lines of force which will progress indefinitely to the left

along the concentric conductor system 3'-2. It will readily be seen that whether the waves are to be propagated on one side as waves in a concentric conductor system or as waves in a dielectric guide, they may be reflected on the opposite side with their energy in either form.

Fig. 9 is a diagrammatic cross-section and Fig. 10 is a corresponding longitudinal section of a combined dielectric guide and three-electrode vacuum tube source for the generation and propagation of asymmetric electric waves within the guide. The filament-cathode 5 comprises two parts on opposite sides of the guide axis and parallel therewith. Around each part of the cathode is a grid 6 having its cross-section D-shaped, with rounded corners as shown in Fig. 9. Placed diametrically is a metallic septum 20 between the two grids, dividing the interior of the shell 3 into two half cylinders.

Referring to Fig. 3a, it will be seen that in the asymmetric electric wave the equipotential surfaces, indicated by dotted lines, are D-shaped with rounded corners; the grids 6 of Figs. 9 and 10 are shaped approximately to follow such an equipotential surface. A tolerable approximation would be attained if the grids were of circular cross-section. Also, the septum 20 lies in an equipotential surface.

The grid 6 is positive, and the plate electrode consisting of the shell 3 and the septum 20 is negative, so that the electrons from the cathode 5 oscillate through the grid along the lines of force such as shown in Fig. 3a, and generate the corresponding type of electromagnetic displacement waves. These waves are propagated from the generator both ways along the tube 3. One way, they are reflected at 24 according to the principles explained in connection with reflector 4 in Fig. 8.

On the opposite side from the reflector 24 is the screen of wires 21 shown in Figs. 9a and 10, which lies in great part across the electric lines of force of the wave. This screen 21 absorbs components in other directions than across its wires, acting as a sieve to purify the waves to the asymmetric electric type.

The septum 20 is not a necessary element and may be omitted, or it may be retained and only one filament and its corresponding grid be employed at one side, those parts shown on the other side in Figs. 9 and 10 being omitted.

The combined structure of dielectric guide and two-electrode vacuum tube shown in longitudinal section in Fig. 11 is adapted for the generation and propagation of symmetric magnetic waves. Within the cylindrical metal anode 1 is an axial cathode 5, both comprised in the power circuit having the battery 41. Glass end seals 9 and 9' are provided, and the space between them and within the anode 1 is evacuated. At its ends the tubular anode 1 has flaring conical extensions 42 which connect with the cylindrical shells 3 and 3' respectively. Surrounding the anode 1 are the core 43 and the winding 44 of an electromagnet, which has axial symmetry with respect to the cathode 5. A direct current through this winding 44 obviously establishes a strong magnetostatic field having longitudinal lines of force within the anode 1 and around the cathode 5.

In the absence of the field due to the winding 44 the electron discharge from the cathode 5 to the anode 1 would be along radial lines. The presence of this field causes a deflection of the electrons. With a comparatively weak field an electron path may be as at 45 in the cross-section

shown in Fig. 12. A stronger field will give such a path as at 46, and a yet stronger field may deflect the electrons so that they will not arrive at the anode 1 but will be constrained to return 5 in a circuit to the cathode 5, as indicated at 47. The volume of current from the cathode 5 to the anode 1 will be only slightly affected by increasing the strength of the field due to the winding 44, if this merely changes the electron trajectories from the shape at 45 to that at 46. But a change as from 46 to 47 gives a decided change in the volume of current. Accordingly, a plot of the current against the strength of field due to the winding 44 has the shape shown in 10 Fig. 13. An adjustment at or near the knee of this curve is the best for the development of suitable oscillatory operation.

There is an adjustable reflector 34 at the left of Fig. 11. Any irregularity in the discharge 20 from the cathode 5 to the anode 1 generates a wave which travels to the left, existing as a dielectric displacement current wave within the shell 3'; this wave goes to the reflector 34, thence back to its source, where it momentarily enhances the discharge current. Thus, in somewhat 25 the manner described heretofore in other cases, the period of the to-and-fro wave on the left stabilizes the frequency of an oscillatory discharge across the cathode 5 and the anode 1. Corresponding electromagnetic waves are generated 30 and sent out along the dielectric guide 3 to the right. These waves have their origin in electronic oscillations along paths such as 47 in Fig. 12. It will readily be seen that as lines of force 35 these paths combine to give a resultant having a substantial circular component, coaxial with the axial cathode 5. There is a screen of radial wires at 48 which purifies the waves through it to bring them to the symmetric magnetic type. Beyond 40 this screen 48 is an adjustable iris 49 for volume control. Thus the waves sent along the dielectric guide having the shell 3 have their lines of electric force as shown in Figs. 2 and 2a and are symmetric magnetic waves.

In the modification shown in Fig. 14, a cylindrical, coaxial grid 6 is introduced. This is made 45 positive and the plate electrode 1 is made negative. The magnetostatic field indicated by the arrow 50 is present, the same as in Fig. 11. Without 50 this field, the electron paths and the lines of force would be as in the cross-section shown in Fig. 15. With this field, the electron paths are given a tangential component in the region between the cathode and the grid. Many of them 55 pass into the space between the grid and the plate, where they are given a tangential acceleration favorable for generating waves with a large component of the symmetric magnetic type.

In the modification indicated by the cross- 60 section of Fig. 16, the coaxial cylindrical grid of Figs. 14 and 15 is replaced by a plurality of plane radial grids 6'. These are positively charged. Their edges nearest the filament provide an accelerating electrostatic field which, in conjunction 65 with the magnetostatic field such as indicated by the arrow 50 in Fig. 14, gives to the electrons a motion with a substantial tangential component. The outer parts of the grids 6' of Fig. 16 enforce further tangential acceleration of the 70 electrons passing through their meshes. It will be noticed that these radially disposed grids 6' in Fig. 16 lie in equipotential surfaces of the symmetric magnetic type of wave, and therefore they do not interfere with the regular transmission of 75 such a wave.

One way to obtain the asymmetric magnetic type of wave is to make the imposed magnetostatic field asymmetric with respect to the axis rather than symmetric as was done in Fig. 11. An electromagnet with suitably directed cores and 5 air gaps may be provided for this purpose, but a special construction is shown in cross-section in Fig. 17. This is similar to Fig. 11, except for the principal distinction that the magnet core 43 and winding 44 have been removed and in 10 Fig. 17 two large conductors 48' and 49' have been connected at diametrically opposite points of the anode shell 1. A current of low voltage but high amperage is sent through the circuit of these two conductors. The lines of current 15 flow in this circuit split from the conductor 48', half going around one side of the shell 1 and half around the other side to unite in the conductor 49'. This large current establishes an interlinked magnetostatic field of considerable magnitude. 20 As viewed in Fig. 17, the lines of magnetic force go away from the observer in the region marked 51 and come toward the observer in the region marked 52.

With such a field, the electrons from the cathode 25 5 are deflected from their normal radial travel toward the plate 1 and are constrained to travel along lines such as indicated in Fig. 17. It will be apparent from this figure that the lines of force of the electric waves have a substantial 30 component parallel with the plane of the tube axis and the axis of the two conductors 48' and 49'. This wave may be reflected on one side and propagated according to the same general 35 plan disclosed for earlier figures. It may be purified to the desired asymmetric magnetic type by a sieve like that indicated at 21' in Fig. 18.

It will be seen that in the foregoing disclosures, to a great extent, a desired type of electromagnetic wave has been established by constraining 40 electrons to oscillate along paths which are the lines of electric force of the desired waves. In the foregoing cases these constrained electron paths have been established within vacuum tubes by means of suitable electric and/or magnetic 45 fields imposed upon the spaces within those tubes. But a suitable constraint may be imposed on the electrons by other means.

At the ends of the aligning cylindrical conductors 61 and 62 of Fig. 19 are the opposite 50 spherical knobs 63 and 64. This system is axially disposed in the guide shell 3. An intermittent spark discharge is maintained across the gap 63-64 by means of the associated direct current power circuit 65. The lines of force of the oscillatory spark gap discharge are whipped off and closed into loops, which are propagated right and left. Those going to the left are reflected by the reflector 4 and return to the right and augment the waves which go initially to the right. 60 The member 61-63 is supported through the insulator 4" by the reflector 4-4', and the member 62-64 is supported by one or a few radial wires or rods 66 which are of considerable resistance and therefore do not interfere substantially with the waves, even though the lines of force have components in their direction. These wires or rods 66 carry the charging currents for the member 62-64. The oscillatory discharge between the members 63 and 64 has a certain 65 natural period and the reflector 4 is adjusted so that the reflected waves will be in phase with the waves that go directly to the right.

Fig. 20 shows a spark gap system adapted for the generation and propagation of the same type 75

of symmetric electric waves. The discharge occurs principally at the gap 10 between the electrodes 71 and 72. It sets up waves which travel along the concentric conductor system comprising the outer shell 3 and the inner cylinder or core 72. The radii of these two members are such as to give an impedance match to the metal-shell air-core guide 3-7 at the right.

For the generation of asymmetric electric waves by means of spark discharges, the apparatus shown in longitudinal section at Fig. 21 and in cross-section at Fig. 22 may be employed. Associated respectively with the spark gap knobs 63' and 64' are the solid D-shaped conductor bodies 76 and 77. The lines of electric force between these bodies 76 and 77 will correspond to the lines of electric force shown in Fig. 3a for asymmetric electric waves. With a proper adjustment of the reflector 34 the waves will be enhanced at the natural frequency of the oscillating system and the lines of force will be detached from the D-shaped electrodes and will be propagated to the right as asymmetric electric waves. They may be purified by a sieve 21' like that shown at 21 in Figs. 9a and 10.

An electrode system for generating asymmetric magnetic waves from spark discharges is shown in longitudinal section in Fig. 23 and in cross-section in Fig. 24. The metal half cylinders 80 and 81 are insulated from the shell 3 and conductively connected to the respective spark discharge knobs 63'' and 64''. During the discharge oscillations the current paths in the conductor system at a given instant will be as indicated by the arrows in Fig. 24. A reflector 34 will be employed as shown in Fig. 23. Asymmetric magnetic waves will be thrown off right and left; those to the left in Fig. 23 will be reflected and will come back to the spark gap. The reflector 34 will be properly adjusted so that the returning waves will enhance the outgoing waves and the radiation to the right will be of approximate asymmetric magnetic waves. These may be purified by a sieve 21' like that shown in Fig. 18.

45 For the generation of symmetric magnetic waves, a system of electrodes and conductors such as shown in Figs. 25, 26 and 27 may be employed. Within the metallic sheath 3 is a figure-8 shaped frame carrying a pair of spark gap members 90 and 91 with the axis of the gap across the axis of the guide. The insulation at 92 and 93 in the figure-8 frame interrupts a conductive path between the members 90 and 91 for direct currents, but permits a path for high frequency 50 alternating currents. The conductors adjacent to either such insulating body 92 or 93 may be regarded as the plates of a condenser. The oscillatory discharge currents flow along the members of the figure-8 frame as indicated by the arrows 55 in Fig. 27, charging and discharging the condensers at 92 and 93, and generating symmetric magnetic waves. Adjacent to the discharge knobs 90 and 91, the currents in the figure-8 frame flow in opposite directions on opposite 60 sides of the gap, thus producing a null effect in the region, so far as those currents are concerned. Symmetric magnetic waves are radiated to right and left, viewing the apparatus as in Fig. 25. On one side, these waves are reflected at 34 and returned to enhance the waves on the other side. The electric lines of force of these waves being circumferential, they may be purified by the sieve 94 on the right having radial wires.

75 In all of Figs. 19 to 27, ordinary open air gaps

are shown by way of example. They may be electron discharge devices within a considerable variety of choice. For spark discharges the knobs may be of zinc in air at various pressures or in oil, or a mercury spark with an atmosphere 5 of hydrogen may be provided. In any case the oscillatory movements of the electrons are along paths which conform to lines of force of the desired waves, and those waves may be regarded as being produced comparatively directly from 10 the oscillatory electrons. It is obvious that the adjustable iris shown by 49 in Figs. 11 and 24 above may also be used in connection with other sources of waves shown. Such a device not only controls the volume but it may be so used as 15 to more clearly define the frequency of oscillation.

In the appended claims, "transverse" means transverse to the axis of the wave-guiding structure or to the direction of wave propagation. 20

I claim:

1. In combination, a wave guide consisting essentially of a metallic pipe and means for generating within said pipe for propagation there-through an electromagnetic wave having a certain characteristic electric field pattern and a frequency higher than a cut-off frequency dependent on a transverse dimension of said pipe, said generating means comprising means within said pipe for producing free electrons and means 30 for impelling said electrons to oscillate with a substantial component of motion along lines corresponding to the lines of force of said electric field.

2. The method of launching dielectrically 35 guided waves in a wave guide comprising a gaseous dielectric medium and metallic means defining the periphery thereof, which comprises projecting free electrons within said medium and subjecting said electrons to an equilibrium field 40 so directed as to cause said electrons to oscillate along paths conforming with the lines of electric force of said dielectrically guided waves.

3. In combination, a dielectric guide, a source of free electrons within said guide, means for 45 causing said free electrons to oscillate and means for constraining the oscillations of said electrons to such paths that there are generated in and propagated through said dielectric guide, electromagnetic waves characterized in that they are 50 readily transmitted through said guide only at frequencies above a critical frequency functionally related to the transverse dimensions of said guide.

4. In combination with a wave guide comprising 55 a metallic pipe enclosing a gaseous dielectric medium, means for launching dielectrically guided waves in said pipe comprising an electron emitting cathode therein, a corresponding anode, and means comprising a third electrode to establish an equilibrium position for electrons emitted from said cathode, said electrons being caused to oscillate about said equilibrium position in such manner that the waves in the lines of force extending through said dielectric medium from said electrons substantially conform with a type of dielectrically guided waves.

5. In combination, a dielectric guide, walls enclosing a vacuum chamber within said guide, 70 means to establish an electron discharge within said chamber, and a reflector across said guide, one way from said chamber, whereby the electron discharge will fluctuate at a period determined by the period of wave travel from the 75

- place of the discharge to the said reflector and back.
6. In combination, a metal sheathed dielectric guide, walls enclosing a coaxial vacuum chamber within the guide, a cathode and a grid and a plate electrode all coaxially placed in said chamber, a coaxial shell in substantial continuation one way from said grid, means to make the grid positive and the plate negative, and an annular reflector between said coaxial shell and the metal sheath of the guide so positioned that concentric conductor system waves around said shell will be reflected and enforce an optimum frequency for the radiation of dielectric displacement waves the other way.
7. In combination, a metal sheathed dielectric guide, walls enclosing a vacuum chamber within the guide, an inner coaxial member extending one way from the chamber and forming a coaxial conductor system with the metal sheath of the guide, an annular reflector between the metal sheath and said member, and means to establish an electron discharge within said chamber, said reflector being adjusted so that concentric conductor system waves thereto will return at the proper period to enforce fluctuations of the discharge in said chamber, whereby dielectric displacement waves in the guide will be radiated the opposite way from the reflector.
8. In combination, a dielectric guide, means to establish a transverse electron discharge within said guide whereby any irregularity of the discharge will propagate a wave both ways along the guide, and a reflector on one side to return such wave and thereby establish a regular fluctuation of the discharge at the period of the to-and-fro waves, whereby there will be sustained radiation of waves the other way along the guide from the reflector.
9. In combination, a dielectric guide, means to establish an electron discharge within said guide with the electron paths directed along desired lines of electric force of a particular type of dielectrically guided waves to be generated, and means to make the electron discharge fluctuate in amplitude in regular periods, whereby such waves will be generated and propagated along the guide.
10. In combination, a metal sheathed dielectric guide, walls enclosing a gas-tight chamber within the guide, coaxial electrodes within and coaxial with the said chamber, and means to establish a fluctuating discharge symmetric with respect to the axis of the guide and in energy transfer relation with waves of symmetric type propagated along the guide.
11. In combination, a dielectric guide, and means for generating asymmetric waves within said guide for propagation therethrough comprising means to establish an electron discharge within the guide with the electron paths principally across a plane of symmetry of the guide and means to cause a fluctuation in the intensity of the discharge in these paths.
12. In combination, a dielectric guide, walls enclosing a chamber within the guide, means within the chamber to produce an electron discharge with the electron paths in large part directed across a plane of symmetry of the guide, and means to produce regular amplitude fluctuations of the discharge current, whereby asymmetric electric waves will be generated and propagated along the guide.
13. In combination, a dielectric guide, an electron emitting cathode in the axis of the guide,
- means to generate a magnetostatic field directed along the axis, and means to produce regular periodic fluctuations in the discharge from said cathode whereby electromagnetic waves will be generated and propagated along the guide, said waves having a substantial component of symmetric magnetic type.
14. In combination, a dielectric guide, a coaxial electron emitting cathode within the guide, means to establish a magnetostatic field around said cathode with its lines of force parallel thereto, and a reflector across the guide, one way from said cathode, whereby symmetric magnetic waves will be generated and propagated the opposite way along the guide from said reflector.
15. In combination, a dielectric guide, a pair of spark discharge members within the guide, means to maintain repeated discharges, and a reflector across the guide one way from said members, whereby dielectric displacement waves will be generated and propagated the other way along the guide.
16. In combination, a metal sheathed dielectric guide, two spark discharge members within said guide having their axis across the axis of the guide, and a reflector one way therefrom across the guide, waves occasioned by a discharge across said members being reflected and propagated the opposite way with a substantially definite frequency as dielectric displacement current waves within the guide.
17. In combination, a metal sheathed dielectric guide, spark gap members within said guide having their axis transverse to the axis of said guide, and means to energize them and thereby generate and propagate asymmetric type waves along the guide.
18. In combination, a wave guide consisting essentially of a metallic pipe, means for generating and propagating through said pipe electromagnetic waves characterized by the existence of a cut-off frequency dependent on a transverse dimension of said pipe, said generating means comprising a pair of electrodes and means for maintaining an oscillatory discharge between them, said electrodes being disposed with their axis conforming in direction with electric lines of force in said electromagnetic waves.
19. In combination, a wave guide comprising a metallic pipe containing only a dielectric medium, a pair of elongated electrodes disposed lengthwise within said pipe at one end thereof, means for establishing an oscillatory spark discharge between juxtaposed localized parts of said electrodes, and reflecting means closing said end of the pipe, said electrodes and reflecting means being so spaced as to enhance the oscillatory discharge at the natural frequency of the electrode system.
20. A combination in accordance with the claim next preceding in which said electrodes are of such cross-section and so disposed transversely of said guide that asymmetric electric waves are produced and propagated through said guide.
21. In combination, a wave guide comprising a metallic pipe containing a dielectric medium and carrying therein high frequency electromagnetic waves having a certain characteristic electric field pattern such that the guide presents to said waves the characteristic of a high-pass filter, and a translating device comprising means for producing free electrons within said pipe and means for impelling said electrons to oscillate with a substantial component of motion

- along lines corresponding to the lines of force of said electric field.
22. In combination, a uni-conductor wave guide comprising a metallic pipe containing a gaseous dielectric medium and carrying therein electromagnetic waves characterized by the existence of a cut-off frequency functionally related to a transverse dimension of said pipe, and a translating device within said guide comprising a pair of electrodes and means for maintaining an oscillatory discharge between them, said electrodes being so disposed that said discharge substantially conforms in direction with electric lines of force in said electromagnetic waves.
- 10 23. In combination with a wave guide comprising a metallic pipe for the transmission therein of electromagnetic waves having such characteristic field patterns that they are transmitted only at frequencies above a critical frequency, a discharge device in energy transfer relation with said waves comprising a plurality of electrodes that are coaxial with each other and with said pipe and one of which is in substantial continuation of said pipe.
- 15 24. In combination, a wave guide comprising a metallic pipe containing a gaseous dielectric medium and carrying dielectrically guided waves therein, and a translating device for launching or receiving said waves comprising cathode, grid and plate electrodes that are coaxial with each other and with said pipe, said cathode and grid electrodes being disposed within said pipe.
- 20 25. In combination, a wave guide comprising a gas-filled metallic pipe carrying dielectrically guided waves of symmetric type, a portion of
- 25 said pipe being of reduced cross-section, and a discharge device comprising a plurality of coaxial electrodes disposed in said portion of pipe and coaxial therewith for generating or receiving said waves.
- 30 26. A combination in accordance with claim 25 in which one of said coaxial electrodes comprises said pipe.
- 35 27. In combination, a wave guide comprising a metallic pipe, an ultra-high frequency oscillation generator comprising a hollow electrode and at least one other electrode within said hollow electrode, and a metallically bounded chamber, one end of said hollow electrode opening into said chamber and the other end into said pipe, the only dielectric path between said chamber and said pipe being through the interior of said hollow electrode.
- 40 28. A combination in accordance with claim 27 in which said pipe, electrodes and chamber are coaxial with each other.
- 45 29. A hollow metallic pipe for the transmission of dielectrically guided waves and an electronic oscillation generator adapted for operation at a frequency of the order of a billion cycles per second, said oscillation generator comprising a hollow electrode of comparatively small cross-section coaxial with said pipe and metallically continuous therewith and another electrode within said hollow electrode, said electrodes being so constructed and arranged as to establish an energy transfer relation between said dielectrically guided waves and said oscillation generator.

GEORGE C. SOUTHWORTH. 35
